LAWN RAKE

Samuel W. Rothwell, 5624 N. G St.,
Spokane, Wash.

Filed May 2, 1969, Ser. No. 16,987

Term of patent 14 years

Int. Cl. D8—01

U.S. Cl. D8—13

FIG. 1 is a top perspective view of the lawn rake, with the outer end of the attached handle being broken away to indicate indeterminate length;

FIG. 2 is a bottom plan view of the lawn rake as shown in FIG. 1;

FIG. 3 is a side view of the lawn rake shown in FIG. 1.
I claim:

The ornamental design for a lawn rake, as shown and described.
